UNITED STATES PATENT OFFICE.

WALTER LACHMANN, OF DRESDEN, GERMANY.

PROCESS AND APPARATUS FOR UTILIZING LIQUEFIED GASES.

Application filed January 3, 1921. Serial No. 434,834.

To all whom it may concern:

Be it known that I, WALTER LACHMANN, a citizen of Germany, residing at Dresden, Germany, have invented certain new and useful Improvements in Processes and Apparatus for Utilizing Liquefied Gases, of which the following is a specification.

In autogenous welding and cutting only the highly compressed oxygen gas contained in steel cylinders, which are cumbersome and costly to transport, has hitherto been employed.

The present invention relates more especially to the afore-mentioned working of metals and is chiefly intended for factories where blasting air and the like is produced. The object of the invention is to enable factories of this kind to substitute gaseous oxygen obtained from suppliers by liquid oxygen produced by themselves, which may be stored and transported in the known extremely light vessels for liquid air with exceedingly small loss by evaporation.

The idea underlying the invention is as follows:

The liquid oxygen is poured into an "auxiliary vessel", which is capable of resisting high pressure and in which no direct contact occurs between the liquid oxygen and the wall of the vessel. From the auxiliary vessel the liquid oxygen is conducted to some other desired place or transferred to suitable vessels such as ordinary steel cylinders which are then used in the known manner. During this transferring process heat is supplied causing evaporation whereby a pressure of, say, 50 atmospheres or more is reached.

The invention will now be described with reference to the accompanying drawing in which—

Fig. 1 is a vertical section of a vessel constructed in accordance with the present invention, the dash lines indicating a cap or closing member;

Figs. 2, 3, and 4 are views similar to Fig. 1, but each illustrating a modified form of vessel;

Figs. 3^a and 4^a are transverse sectional views taken respectively on the lines A—A of Fig. 3, and B—B of Fig. 4;

Fig. 5 is a vertical sectional view of a cap adapted for closing either of the vessels shown in Figs. 1 to 4; said cap being provided with means for charging the vessel;

Figs. 6 to 14, inclusive are views similar to Fig. 5, each illustrating a modification of

the charging means, the interior or receiving vessel being indicated diagrammatically in these figures.

Referring to the drawings, and especially to Figs. 1 to 4, inclusive, the vessel comprises a double-walled vessel, the space between the inner wall 1 and the outer wall 2 of which is evacuated, whereby the insulating qualities of the vessel are rendered as perfect as possible and spontaneous evaporation reduced to a minimum, while the desired evaporation may be regulated and controlled at will. The inner wall 1 is of sufficient strength to sustain a pressure of at least 50 atmospheres. The vessel may be spherical, but it is preferably of tall cylindrical form as illustrated in the drawings, and provided with the usual dome-shaped bottom and top as in the well-known steel cylinders or bottles, the top or cover being either formed integral with the main cylinder or body portion or secured thereto by means of annular flanges as shown in the drawings.

For further retarding the radiation of heat to the liquid oxygen, and consequently reducing the spontaneous evaporation thereof, a thin walled vessel is provided adapted to be placed within the double walled vessel above described, and which constitutes the receiving vessel proper. This receiving vessel may itself be formed of a material which is a poor conductor of heat, such for instance as pressed paper and vulcanite, porcelain as shown at 4 in Fig. 1, or any other suitable material, such as quartz or thin glass, or the receiving vessel may be made of thin sheet metal, as shown at 4^a in Fig. 2, and separated from the outer vessel by a suitable heat-insulating material. In either case, it is highly desirable that the receiving vessel contact as little as possible with the outer vessel, and for this reason the wall of the receiving vessel is spirally grooved or corrugated at its exterior as shown in Figs. 1 and 2, and as it is particularly desirable to avoid all contact when the receiving vessel is made of sheet metal, in Fig. 2 I have shown an insulating material 5 interposed between the two vessels, which insulating material may consist of leather, felt, canvas, asbestos, cork, compressed paper or vulcanite. In Figs. 3 and 4, the receiving vessel 4^b is shown with the outer surface of its wall smooth. In Fig. 3, however, a wire netting 6 is inserted between the insulating material

80

5 and the inner wall of the outer or auxiliary vessel, while in Fig. 4, the insulating material above referred to is omitted and a corrugated heat-insulating material 7, such 5 for instance as the well-known corrugated cardboard, substituted therefor. It will thus be seen that in all forms of the vessel provision is made for the rapid propagation of pressure, so that any pressure arising 10 within the vessel is permitted to spread quickly into the space between the receiving vessel and the outer vessel.

In Figs. 5 to 14, I have illustrated a suitable cap 8 for closing the vessel, said cap 15 having an annular flange at its lower end adapted to be bolted to the flange of the vessel. The cap is provided with an interiorly threaded neck 9 adapted to receive the threaded lower end of a funnel-shaped 20 member 11 (as shown in Fig. 5), by means of which the vessel may be filled or charged. To accelerate the charging operation, a small gas injector actuated by compressed oxygen may be used, which injector comprises 25 a small tube 12 that enters the funnel member 11 through the side wall thereof and extends downwardly in said member, the opposite end of the pipe 12 being connected with a convenient supply of oxygen, 30 such as a steel bottle (not shown). The funnel is preferably of double wall construction, the space between the walls being evacuated. By this construction, a jet or stream of oxygen gas is led from the source 35 of supply into the funnel 11, and by reason of the expansion of said gas a current is induced at the delivery end of the funnel, which current carries along with it the liquid oxygen with which the funnel is kept 40 filled, thus considerably facilitating the charging of the vessel. During the charging operation, and particularly at the beginning, oxygen vapor will develop within the vessel. To take care of this vapor the 45 cap is provided with a neck or port 10 in communication with a pipe 14, which in turn is connected to a convenient oxygen holder or tank (not shown). The cap is also provided with another port or neck 10^a for connection with a suitable pressure gage. The oxygen holder with which the pipe 14 is connected may be caused to have a sucking effect on the vapor in the vessel by placing the pipe 14 also in communication with the tube 12 through a tube 13, whereby the liquid oxygen will be caused to flow in much faster. It is important 50 that the charging funnel be constantly kept filled with liquid oxygen during the charging operation, or provision must be made for quickly closing it so as to prevent air from being sucked into the vessel.

For discharging the oxygen from the vessel hereinbefore described into the vessel for 60 ordinary use, such as the usual steel cylinders

or bottles, either of two preferred methods may be used, namely, the oxygen may be vaporized within the receiving vessel before transferring it to the bottles, or it may be discharged from the receiving vessel in liquid form and vaporized either on its way to the bottles or after it reaches the bottles. In the present instance I have illustrated apparatus for delivering the oxygen in either or both of these forms. Referring first to Fig. 6, an apparatus is shown therein which is specially adapted for delivering the oxygen in vaporized condition by the application of heat within the container or vessel. The agent for conveying the heat is oxygen 80 gas, or as termed herein "auxiliary oxygen gas," which may be blown from an ordinary steel bottle into the liquid oxygen in the vessel through a pipe 17 that passes through a threaded sleeve 16 which is substituted in 85 the neck 9 of the cap in place of the funnel 11, and which sleeve is provided with a hexagonal collar that seats on the end of said neck, as shown in Fig. 6. The pipe 17 extends down nearly to the bottom of the vessel 90 4. For the sake of economy in the use of the auxiliary oxygen gas, said gas may be heated before introducing it into the vessel, by any suitable means, such for instance as a burner 18, as shown in Figs. 6 and 7. A further extremely large saving of auxiliary oxygen may be effected by providing a device resembling an injector, by means of which a current will be induced by the auxiliary oxygen so as to carry along with it 100 the gaseous oxygen vaporized within the vessel itself. Such a device is illustrated at 20 in Figs. 6 and 7, wherein the portion of the pipe 17 extending near to the bottom of the vessel is encircled by a larger pipe 19, the upper end of which is funnel-shaped, and the lower end of which extends below the pipe 17. From this construction it will be obvious that as the so-called auxiliary oxygen is discharged at the end of pipe 17 110 within the portion 20 of the pipe 19 a current will be induced which will suck into the funnel-shaped upper end of said pipe the gaseous oxygen immediately around and above it thereby causing a circulation of said oxygen as indicated by the arrows. As the oxygen becomes vaporized and the pressure increases within the vessel, the vaporized oxygen will pass out through the neck 10 and pipe 14 to the place of use, or into the 115 usual steel bottles or cylinders.

In Fig. 7 is illustrated one form of apparatus for delivering the oxygen from the vessel in liquid form. The device is substantially like that shown in Fig. 6, the only 120 difference being that an additional tube 21 is provided at the interior of the vessel, and which tube reaches nearly to the bottom of the vessel and communicates at its upper end through the neck 10 with the tube 14. 130

In this case the oxygen that is vaporized within the vessel exerts its pressure on the surface of the liquid oxygen and forces the same up through the tube 21 and tube 14, to 5 the place of use.

In Fig. 8 is shown a modified structure, in which the cap 8 is provided with a removable sleeve 22 threaded into the neck 9 and carrying a tube 23 that extends nearly to the 10 bottom of the vessel. In this form, the charging funnel 11^a is threaded on the upper end of the sleeve 22. The device operates in the same manner as that illustrated in Fig. 5, except that the liquid oxygen is 15 delivered at the bottom of the vessel. When the contents of the vessel are to be discharged in gaseous form, the funnel 11^a is removed from the sleeve 22 and the pipe 17, shown in Fig. 12, which in this instance is provided 20 with a swivelled head 25 interiorly threaded for connection with the sleeve, is substituted in place of said funnel. The apparatus will then operate in a manner similar to that described in connection with Fig. 6. That is 25 to say, the so-called auxiliary oxygen led in by the pipe 17 is delivered by pipe 23 at the bottom of the vessel, the heat thereof causing vaporization of the liquid oxygen, the gaseous oxygen being conducted away 30 through the pipe 14 to the place of use. When, however, the oxygen is to be discharged in liquid form, the apparatus shown in Fig. 9 may be substituted for that of Fig. 12. In this form, a head 26 is provided which fits on the upper end of the sleeve 22, which head carries a tube 17^a for admitting auxiliary oxygen to the tube 23, and also carries a tube 21^a which is smaller than and passes down through tube 23 to the 35 bottom of the vessel. This apparatus operates in a manner similar to that shown in Fig. 7. In other words, the auxiliary oxygen passes down through tube 23, around tube 21^a, and bubbles up through the liquid 40 oxygen, thereby heating the same and causing vaporization, the vaporized oxygen exerting pressure on the surface of the liquid oxygen and forcing the latter up through pipe 21^a to the place of use. In this instance, 45 the neck 10 may be sealed by a suitable disk 50 27 secured thereto in any suitable manner.

In Figs. 10, 11, 13, and 14 are illustrated various forms of combined apparatus for charging and discharging the vessel, the 55 discharging apparatus being valve-controlled, whereby at the will of the operator, and without the removal of any parts, the vessel may be made to discharge either gaseous or liquid oxygen. In the device shown 60 in Fig. 10, for example, the filler funnel and liquid oxygen inlet tube are identical with that of Fig. 8, and a valve-controlled additional tube 21^b passes through the wall of the sleeve 22 and extends down through tube 23 to the bottom of the vessel. A

valve housing 28 is threaded into the neck 10 of the cap for controlling the flow of gaseous oxygen to the pipe 14^a. In this form of the apparatus, when the vessel is to be filled the valve in pipe 21^b is closed and 70 the valve controlling the pipe 14^a may or may not be left slightly opened to carry off the vaporized oxygen thereby to relieve the pressure and facilitate the charging of the vessel in the manner described in connection with Figs. 5 and 8. If after the vessel is filled, it is desired to discharge the oxygen therefrom in liquid form, the valve in housing 28 is closed, while the valve controlling the pipe 21^b is opened, whereupon pipe 12 may be used to supply the auxiliary oxygen hereinbefore referred to for increasing the surface pressure and forcing the liquid oxygen up through the pipe 21^b. On the other hand, if the oxygen is 80 to be discharged in gaseous form, the valve in pipe 21^b is closed while that in housing 28 is fully opened, whereupon the vaporized oxygen will flow freely through pipe 14^a, the vaporization being facilitated 85 by the auxiliary gas supplied by pipe 12. In Fig. 11, the apparatus is the same as that of Fig. 10, excepting that the pipe 21^b, instead of passing down through pipe 23, passes through the valve housing 30 in 90 neck 10. The location of the pipe 21^b in this instance is similar to that of pipe 21 in Fig. 7. The valve housing 30 is provided with an enlarged chamber and an admission port communicating with the interior of the vessel, whereby gas is freely admitted to the chamber around the pipe 21^b. The pipe 14^b communicates by means 95 of a valve controlled port with said chamber. The operation of this device is substantially the same as that of Fig. 10. The devices illustrated in Figs. 13 and 14 are 100 identical with those of Figs. 10 and 11 respectively, except that in place of the funnel 11^a and pipe 12, a pipe 17 similar to that described in connection with Fig. 12 is used. In this case, the pipe 17 may be used for filling the vessel, and may also be used for supplying the auxiliary oxygen hereinbefore referred to for heating the liquid oxygen and facilitating the discharge 105 of the vessel.

The auxiliary vessel may also be employed, like the steel bottles, for transport and ordinary use.

The invention is not only applicable for autogenous metal working but in all processes employing oxygen under pressure.

The processes and devices described above are not only adapted for transferring liquid oxygen from one vessel to another but also for dealing in a similar manner with other gases that are hard to condense such as nitrogen, carbonic oxide, methane, hydrogen, and easily-condensed gases and va- 125 130

pors such as ethylene, ethane, hydric sulphide, chlorine, methylic ether, ammoniac, carbonic acid, sulphurous acid, and nitrous oxide. It is well known that the last named 5 gases are used in large quantities for the artificial production of cold, as well as ethylene and ethane are employed for illumination, welding and all manners of processes of combustion. The application 10 of the described process and devices to these gases results in reduced costs for transportation and other advantages. Under certain circumstances the vessel for holding 15 liquid air may be made in the shape and size of the tank carriages used for the transportation of petroleum and the like.

The consideration that led to the invention hereinbefore described was that the construction of vacuum vessels which will 20 resist high pressure and at the same time give rise to only the small losses by evaporation caused in the known vacuum vessels appears to be quite out of the question.

I claim:

25 1. An auxiliary containing-vessel for liquefied gas comprising a shell, a gas receiving vessel composed of a poor conductor of heat in the said shell, and an intermediate body sandwiched in between the shell 30 and the receiving vessel, the intermediate body being adapted to permit of a rapid propagation of pressure in the space between the receiving vessel and the shell.

35 2. An auxiliary containing-vessel for liquefied gas comprising a shell, a gas receiving vessel composed of a poor conductor of heat in the said shell and a strong metal network sandwiched in between the receiving vessel and the shell, whereby a rapid 40 propagation of pressure between the receiving vessel and the shell is rendered possible.

45 3. An auxiliary containing-vessel for liquefied gas comprising a shell, a thin-walled receiving vessel in the said shell, and a poor conductor of heat sandwiched in between the shell and the receiving vessel, passages being formed on the wall of the receiving vessel for the rapid propagation 50 of pressure.

55 4. An auxiliary containing-vessel for liquefied gas comprising a shell, and a receiving vessel with a thin wall formed with protuberances in the said shell, whereby advantage is taken of the heat-insulating properties of air.

60 5. An auxiliary containing-vessel for liquefied gas comprising a shell, a thin-walled receiving vessel in the said shell and corrugated insulating material sandwiched in between the shell and the receiving vessel, whereby passages are formed for the rapid propagation of pressure in the intermediate space between the shell and the receiving vessel, and advantage is taken of the heat-insulating properties of air.

6. An auxiliary containing-vessel for liquefied gas comprising a vessel of good heat-insulating properties, a permanently fixed pipe extending almost to the bottom of the vessel for conducting liquefied gas 70 into the vessel and for subsequently blowing auxiliary gas into the said vessel and a secondary pipe inserted in the permanently fixed pipe extending to the bottom of the vessel during the transference of liquefied gas from the containing-vessel, and adapted to operate as an ascension pipe for the liquefied gas, a clear space being left between the two said pipes, and the joint of and between the pipes being gas-tight. 75

80 7. An auxiliary containing-vessel for liquefied gas comprising a vessel of good heat-insulating properties and two permanently fixed pipes extending to the bottom of the vessel and arranged one within the other, the outer pipe being adapted to conduct liquefied gas into the vessel, and the outer pipe being adapted for subsequently blowing in warm auxiliary gas, and the inner pipe being adapted for conducting 85 liquefied gas out of the vessel.

85 8. An auxiliary containing-vessel for liquefied gas comprising a vessel of good heat-insulating properties and two permanently fixed pipes one within the other, the outer pipe being adapted to conduct liquefied gas into the vessel, and the two pipes being adapted for subsequently blowing in warm auxiliary gas, and conducting 90 liquefied gas out of the vessel, either of the pipes being adapted for either of these two functions.

9. An auxiliary containing-vessel for liquefied gas comprising a vessel of good heat-insulating properties, and two permanently fixed pipes one beside the other, the one pipe being adapted to conduct liquefied gas into the vessel, and the two pipes being adapted for subsequently blowing in warm auxiliary gas and conducting 105 liquefied gas out of the vessel, either of the pipes being adapted for either of these two purposes.

10. An auxiliary containing-vessel for liquefied gas comprising a vessel of good heat-insulating properties, and two permanently fixed pipes one beside the other extending to the bottom of the vessel, the one pipe being adapted to conduct liquefied gas 110 into the vessel, and for subsequently blowing in warm auxiliary gas and the other pipe being adapted for conducting liquefied gas out of the vessel.

115 In testimony whereof I have signed this specification in the presence of two witnesses.

WALTER LACHMANN.
